ATTORNEY

UNITED STATES PATENT OFFICE.

GEORGE E. McCONNELL, OF AURORA, ILLINOIS.

VELOCIPED.

Application filed August 27, 1923. Serial No. 659,577.

To all whom it may concern:

Be it known that I, GEORGE E. McCONNELL, a citizen of the United States, residing at Aurora, in the county of Kane and State of Illinois, have invented new and useful Improvements in Velocipedes, of which the following is a specification.

This invention relates to toys and more particularly to a toy of the type such as commonly known as scooters, and an object of the invention is to provide a device of this type which embodies a simple, practical driving mechanism which is operatively connected to the rear axle of the scooter to permit the scooter to be propelled with relatively small effort on the part of the child operating it.

Another object of this invention is to provide a scooter or toy as specified which embodies means whereby the normally idle movement of the operating lever is converted into a power generating movement, thereby causing application of driving power to the driving axle of the scooter upon both the upward and downward movements of the operating pedal or lever.

Other objects of the invention will appear in the following detailed description taken in connection with the accompanying drawings wherein:

30 Fig. 1 is a side elevation of the improved scooter.

Fig. 2 is a top plan of the scooter.

Fig. 3 is a vertical section on the line 3—3 of Fig. 2.

35 Fig. 4 is a vertical section on the line 4—4 of Fig. 2.

Fig. 5 is a detail section taken on the line 5—5 of Fig. 3.

40 Fig. 6 is a detail section on the line 6—6 of Fig. 3.

Fig. 7 is a fragmentary vertical section, showing parts broken away and taken on the line 7—7 of Fig. 2.

45 Referring more particularly to the drawings, the improved wheeled toy or scooter comprises a supporting frame 1 which is preferably constructed of a single piece of bar metal and comprises the side rails 2 upon which the platform 3 is supported, and

50 which have the rear driving axle 4 carried by their rear ends. The forward ends of the rails 2 are bent inwardly and upwardly as shown at 5, and are connected by a suitable coupling structure of any approved type as indicated at 6 to the fork 7, the lower end of which carries the front axle 8 while

the upper end carries a gripping handle 9.

The rear drive axle 4 has a pair of driving wheels 10 thereon and it also has a gear 11 mounted thereon which meshes with a gear 12 carried by the shaft 13.

Braces 14 are carried by the platform 3 and have their free ends inserted through the platform, and bent to lie in abutting engagement with the under surface of the platform 3 and the inner sides of the rails 2, as clearly shown in Fig. 4 of the drawings.

A shaft 15 is carried by the upper ends of the braces 14, and it has an operating lever 16 rockably mounted thereon, the forward end of which lever is widened to provide a foot rest as shown at 17 which has up-standing flanges 18 on its ends so as to prevent a child's foot from sliding off the foot rest.

The operating lever 16 has a rearwardly extending arm 19 formed thereon and a downwardly extending arm 20 formed thereon. The rearwardly extending arm 19 has a cord 21 connected thereto which is coiled about a drum 22 mounted on the shaft 13.

The shaft 13 is supported by suitable inwardly extending extensions 24 formed on the side rails 2. The drum 22 is connected to the shaft 13 through the medium of a coil spring 25 which is tensioned to rotate the drum to wind the cord 21 thereon.

A suitable flange 26 is provided to prevent the cord 21 from moving or slipping laterally off of the drum and the drum is provided with a hub extension 27 which is provided with a plurality of circumferentially spaced peripheral recesses 28. Pawls 29 are pivotally mounted in the recesses 28 and they are urged outwardly into engagement with the ratchet teeth 30 by

85 springs 31. The ratchet teeth 30 are formed on the inner perimeter of a flange 32 formed on one side of the gear 12. The gear 12 has a second flange 33 formed thereon which is provided with internal ratchet teeth 34 with which the pawls 35 cooperate.

The pawls 35 are carried by the drum 36, in the same manner in which the pawls 29 are carried by the drum 22. The cord 37 which is connected to and winds about the drum 36 is connected to the arm 20. A spring 38 is attached to the forward end of the frame 1 and is connected by means of a suitable cord, cable or the like 39 to the arm 20, as clearly shown in Figs. 1 and

7 of the drawings.

The flange 32 has ratchet teeth 40 on its

100

105

110

outer perimeter with which a spring pressed pawl 41 engages to prevent over-running or reversed rotation of the gear 12 and consequently of the rear axle 4 and drive wheels 10 during operation of the device.

In operating the device, when the lever 16 is forced downwardly by the foot of the operator, it will move the arm 19 upwardly and unwind the cord 21 from the 10 drum 22, which will, through the medium of the pawls 29 impart rotation to the gear 12 and then as the downward pressure is relieved on the lever 16, the spring 38, which is tensioned when the lever 16 is moved 15 downwardly, will reflex and through its connection with the arm 20 will move the arm 20 forwardly, and move the lever 16 upwardly during which time the arm 19 will move downwardly. The forward movement 20 of the arm 20 will unwind the cord 37 from the drum 36 which cord has been wound upon the drum 36 during the downward movement of the lever 16 by the coil spring 45. The rotation of the drum 36 will 25 be transmitted to the gear 12 through the medium of the pawls 35 and ratchet teeth 34 which are arranged to rotate the gear in the same direction in which it would be rotated by the drum 22; thus power will 30 be administered to the gear 12 on both the upward and downward movement of the lever 16, which power is transmitted from the gear 12 to the gear 11 and to the driving axle 4 for propelling the vehicle or scooter. 35 It is, of course, to be understood that the invention may be constructed in other manners and the parts associated in different relations and, therefore, I do not desire to be limited in any manner except as set forth 40 in the claims hereunto appended.

Having thus described my invention what I claim is:—

1. A velocipede comprising a driving axle, a pivotally mounted operating lever adapted to be forced downwardly by manual pressure, a spring connected to the lever for moving the lever upwardly, means includ- 45

ing the spring associated with the lever for transmitting driving power to said driving axle upon both downward and upward movement of the lever, and means for preventing reversed rotation of the driving axle. 50

2. A velocipede comprising a driving axle, a platform, an operating lever pivotally carried by the platform, a power transmission shaft, gears connecting said power transmission shaft and drive axle, a rearwardly and a downwardly extending arm connected to said operating lever, 55 means connecting said arms and said gears for rotating the gears positively upon both downward and upward movement of said operating lever, and a spring connected to one of said arms for moving said operating lever upwardly. 60

3. A velocipede of the character described comprising a wheeled supporting frame including side rails, a platform arranged on the frame, parallel spaced braces arising from the platform and having their lower ends bent at right angles and secured to the inner sides of the side rails, an operating lever pivoted intermediate its ends between the braces, a downwardly extending arm formed on the lever at its pivot point, a driving axle rotatably mounted in the rear ends of the side rails, a power transmission shaft gear connecting said shafts for cooperative association, means for driving said power transmission shaft including a pawl actuated means, drums resiliently mounted to the power transmission shaft and adapted to impart rotation to the pawl actuated means, said drums being connected to the operating lever and downwardly extending arm respectively, and a fixed coil spring adapted to rotate said drums and move said operating lever upwardly simultaneously for its downward propulsion stroke. 70 75 80 85 90

In testimony whereof I affix my signature.

GEORGE E. McCONNELL.
